United States Patent Office

Des. 202,950
Patented Nov. 16, 1965

202,950

CALENDAR FILE HOLDER

William F. Vernon, Sr., Newton, Iowa, assignor to The
Vernon Company, Newton, Iowa

Filed Jan. 21, 1965, Ser. No. 83,543

Term of patent 14 years

(Cl. D74—5)

FIG. 1

FIG. 2

FIG. 3

FIG. 4

FIG. 5

FIGURE 1 is a front elevational view of a calendar file holder showing my new design.

FIGURE 2 is an end elevational view thereof as seen from the right of FIGURE 1.

FIGURE 3 is a rear elevational view thereof.

FIGURE 4 is an end elevational view opposite to that shown in FIGURE 2.

FIGURE 5 is a top plan view thereof.

I claim:

The ornamental design for a calendar file holder, as shown.
